United States Patent Office

Des. 213,083
Patented Dec. 31, 1968

213,083

PLACE MAT

Esther Singer Lobar, New York, N.Y., assignor to Singer
Home Products Corp., New York, N.Y., a corporation of New York

Filed Apr. 9, 1968, Ser. No. 11,375

Term of patent 14 years

(Cl. D92—1)

The figure is a top plan view of a place mat embodying my new design, the place mat being of conventional thickness with the pattern applied thereto.

I claim:

The ornamental design for a place mat, as shown.
